UNITED STATES PATENT OFFICE.

BERT C. BALL, OF PORTLAND, OREGON.

CARBURETOR.

Application filed February 16, 1923. Serial No. 619,885.

It is desirable in controlling the flow of fuel and air to carburetors to vary the proportions of the mixture under certain conditions. In some types of carburetors the fuel is delivered to a spray passage and carried in the form of a spray to the mixture passage. This plan has many advantages in that it permits of a nozzle considerably elevated above the point of discharge of the fuel without the disturbing effect of gravity at the low speeds inasmuch as the spray is not materially affected by gravity. In order to control the flow of fuel to the spray passage the flow of air to the spray passage may be varied. In the present invention this is varied automatically as the throttle is varied so that by varying the air opening to the spray passage a richer mixture is delivered as the throttle is opened. I prefer also to control the air passage in connection with a choke valve so that the mixture will be enriched not only by the reduction in pressure incident to the closing of the choke valve but also by reason of the greater restriction or expulsion of air through the spray passage. Other details and features of the invention will appear from the specification and claims.

The invention is illustrated in the accompanying drawings as follows:

Fig. 1 shows a central vertical section through the carburetor.

Fig. 2 a side elevation of the carburetor.

Fig. 3 a section on the line 3—3 in Fig. 2.

Fig. 4 a side elevation, partly in section, on the line 4—4 in Fig. 3.

Fig. 5 a view similar to Fig. 4 but with the parts in a different position.

Fig. 6 a section on the line 6—6 in Fig. 4.

Fig. 7 a plan view of one of the valve seats showing the port leading to the spray passage.

1 marks the carburetor body. This has a mixture passage 2 extending through it. The usual Venturi tube 3 is arranged in the mixture passage and spray nozzles 4 lead into the Venturi tube. A throttle valve 5 is fixed on the shaft 6. It is of the butterfly type and controls the mixture passage in the usual manner. A choke valve 7 is mounted on a shaft 8 and at the inlet end of the mixture passage and operates in the usual manner. A lever 9 is fixed on the shaft 6 and a throttle control rod 10 leads from the lever 9. A similar lever 11 is fixed on the shaft

8 and the usual choke rod 12 leads from the lever 11. A float chamber 13 has an inlet passage 14. This is controlled by a float valve 15. A stem 16 extends from the float valve 15. A spool 17 is arranged on the stem. Levers 18 engage the spool 17 and are in position to be actuated by a float 19 in the usual manner.

A discharge passage 20 leads from the float chamber to a vertical fuel passage 21. A plug screw 22 is arranged in the passage 21. It has the radial openings 23 communicating with the passage 21 and has a central passage 24. A metered opening 25 is arranged at the end of a plug 27 extending downwardly into the passage 21, the plug 27 having a central passage 26 into which the metered opening leads. Radial openings 28 lead through the walls of the plug 27 into a fuel well 29. The fuel well 29 communicates by a spray passage 30 with an annular passage 31 surrounding the Venturi tube and from which the spray nozzles 4 extend.

The operation of this part of the carburetor follows the operation of carburetors of this type. Fuel is delivered by gravity and suction through the passages 28 to the well 29. Air is delivered to the well 29 in the manner described hereafter and sweeps up the fuel and carries it in the form of a spray through the spray nozzles. The pressure in the well varies with the pressure in the mixing chamber, the reduced pressure being communicated through the nozzles. This pressure in the well may be varied by controlling the inflow of air to the well and in the present invention as heretofore stated this is utilized in varying the richness of the mixture.

A spray valve control post 32 extends from the body of the carburetor and leads from the well 29. This has a port opening 34 which leads to a central passage 33 in the post. A valve 35 is rotatively mounted on the post and this has a port 36 which is adapted to be moved into and out of register with the port 34. A screw 39 extends into the opening 33 in the post and secures the valve on the post, this screw having a central passage 40 which communicates with the passage 33 and the ports through radial passages 39a. A lever 41 extends from the valve and this is connected by a link 42 with the throttle control lever 9 so that as the throttle is opened the valve 35 is moved and grad-

ually closes, or nearly closes the valve openings through the ports 34 and 36 when the throttle has reached a pre-determined intermediate position where the richer mixture is desired. By varying the shapes of the ports the variation in the mixture may be changed as desired to correspond with different throttle openings. As shown the port 34 is T-shaped, the main part of the opening having a fairly wide opening 37 which is permanently open and a main port opening 38 which is closed as the valve is swung.

In order to make the choke valve influence the feeding of fuel through the air to the spray passage the valve 35 has an enclosed chamber 43 over the port 36 from which a port 44 leads to a valve opening 45. A port 46 leads to the valve opening 45 and a valve 47 slides in the opening 45. A spring link 48 connects the valve 47 with the lever 11, this link having a slotted end at 49 so as to give some freedom of movement to the choke valve independently of this link and the spring being designed to permit of the free movement of the valve 35 with the choke valve open as indicated in Fig. 5. In starting with the choke valve nearly closed the valve 47 is moved to a position closing the ports 46 and 44 and consequently closes off the air to the spray passage so that the fuel is subjected to the full suction effort of the mixture passage and a very rich flow of mixture follows. As the choke valve is opened the valve 47 is thrown out of action and has no further influence on the introduction of air.

What I claim as new is:—

1. In a carburetor, the combination of a mixture passage; a throttle valve in said passage; a choke valve in the passage; a spray passage leading to the mixture passage; a fuel passage and an air passage leading to the spray passage; and means acting with the throttle and choke valves controlling the air passage.

2. In a carburetor, the combination of a mixture passage; a throttle valve in the passage; a choke valve in the passage; a spray passage leading to the mixture passage; a rotary valve seat having ports leading to the spray passage; a rotary valve on said seat; a connection between said rotary valve and the throttle valve; a choke controlled valve carried by the rotary valve; and a connection between the choke controlled valve and the choke valve.

3. In a carburetor, the combination of a mixture passage; a throttle valve in the passage; a choke valve in the passage; a spray passage leading to the mixture passage; a rotary valve seat having ports leading to the spray passage; a rotary valve on said seat; a connection between said rotary valve and the throttle valve; a choke controlled valve carried by the rotary valve; and a connection between the choke controlled valve and the choke valve, said connection having slack permitting the movement of the rotary valve with the choke valve stationary.

In testimony whereof I have hereunto set my hand.

BERT C. BALL.
